Chas. W. H. Ally =

UNITED STATES PATENT OFFICE

RALPH WISHON, OF CHICAGO, ILLINOIS, ASSIGNOR TO THE TRINDL COMPANY, A CORPORATION OF ILLINOIS

REAMER BAR SUPPORTING BRACKET

Application filed June 27, 1927. Serial No. 201,759.

This invention relates to a reamer bar supporting bracket.

It is an object of this invention to provide a reamer bar supporting bracket adapted to be clamped to a crank case or the like and provided with an arm adjustable as to length and angular relation and carrying a self-aligning bearing for aligning the reamer bar with a main crankshaft bearing or cam-shaft bearing to be reamed.

It is a further object of this invention to provide a reamer bar supporting bracket that may be readily secured at any place along its length to a crank case or the like and that carries a self-aligning bearing which, after alignment with the bearings to be reamed, may be clamped in that position without disturbing the alignment.

Other and further important objects of this invention will become apparent from the disclosures in the following description and appended claim.

In the accompanying drawings which illustrate a preferred embodiment of this invention and in which similar reference numerals refer to similar features in the different views:

Figure 1 is a top plan view of an inverted crank case illustrating the use of devices embodying the principles of my invention in reaming the main crankshaft bearings.

Figure 2 is a sectional view taken on line II-II of Figure 1, with parts in elevation.

Figure 3 is a sectional view taken on line III-III of Figure 1.

Figure 4 is an enlarged sectional view taken on line IV-IV of Figure 3, with parts in elevation and parts removed.

Figure 5 is an enlarged sectional view taken on line V-V of Figure 1, with parts in elevation.

Figure 6 is a sectional view taken on line VI-VI of Figure 5, with parts in elevation.

Figure 7 is an enlarged fragmentary sec-

tional view taken on line VII-VII of Figure 5.

Figure 8 is a transverse sectional view through a crank case illustrating the device in position for reaming a camshaft bearing.

As shown on the drawings:

The reference numeral 1 indicates as a whole a crank case of the type to be found in internal combustion engines. In order to ream out the main crankshaft bearings or the cam-shaft bearings, the crank case 1 is supported in inverted position and a plurality of reamer bar supporting brackets 2 of my invention are secured to the bottom flange 3 thereof, transversely of the length of the crank case.

Each of the reamer bar supporting brackets 2 comprises a pair of bars 4 identical in form and spaced apart by means of spacing bushings 5 through which extend clamping bolts 6. Said bars 4 are of sufficient length to extend beyond the sides of the crank case 1 and are secured to the flanges 3 of said crank case 1 by means of bolts 7 extending between the bars 4 and through apertures 8 in the flanges 3. Washers 9 are provided on the upper ends of the bolts 7 to form a bearing against the upper faces of the bars 4.

Each of said reamer bar supporting brackets 2 is formed with a central enlarged portion 10 having a semi-cylindrical recess 11 formed in the lower edge thereof for alignment with the main crankshaft bearings 12. An adjustable split arm 13 is positioned between the enlarged portions 10 of the bars 4 and for this purpose is provided with an elongated slot 14 for receiving a clamping bolt 15 extending through said enlarged portions 10. Said arm 13, which is thus adjustable as to length and angular relation with respect to the bars 4, carries at its lower end a self-aligning bearing 16. Said bearing 16 is formed with spherical faces 17 (Figure 7) clamping held between the concave spheri-

cal faces 18 of the split arm 13 so as to permit the bearing to be self-aligning. A bore 19 of sufficient size to serve as a guide for a reamer bar 20 extends through said bearing 16.

As shown in Figures 1 to 6 inclusive, a plurality of reamer bar supporting brackets 2 are secured to the lower flanges 3 of the crank case 1 with the recesses 11 in substantial alignment with the main crankshaft bearings 12. A larger bracket 25 is mounted at one end of said crankshaft to provide an external bearing for the reamer bar 20. The bolts 15 are then loosened to permit adjustment of the arms 13 until the bearings 16 are brought into substantial alignment with the main bearings 12. A reamer bar 14 is then inserted through the main bearings 12 and the self-aligning bearings 16 carried by said arms 13. Temporary bushings are placed in the main bearing supports 21 and the reamer bar 20 aligned therein. The bolts 15 are then tightened in a direction parallel to the reamer bar to tightly clamp the arms 13 in the correct position. The temporary bushings and reamer bar 20 are removed and the bearing linings 22 to be reamed secured in place upon the bearing supports 21. The reamer bar 20 is then fitted with adjustable reamers 23, such as described in my co-pending application entitled, "Adjustable reamer", Serial No. 201,757, filed June 27, 1927, and the bar 20 inserted in position in the bearings 16. Said bearings 16 being self-aligning, will automatically center the reamer bar 20 in the correct position for reaming the main bearings 12. The blades of the adjustable reamers 23 are expanded as disclosed in my application above referred to and the reaming process carried out by rotating the reamer bar 20.

It will be apparent that the reamer bar supporting brackets of my invention are thus readily adjustable to any size of crank case and that the self-aligning bearings 16 provide accurate self-centering means for the reamer carrying pilot bar. Since the bolts 15 extend at right angles to the said arms 13, there is no possibility of the bearings 16 getting out of alignment with the main crankshaft bearings 12 after the preliminary alignment during the final clamping operation.

In Figure 8 there is illustrated a reamer bar supporting bracket 2 with the adjustable arm 13 positioned for reaming a camshaft bearing 24. This adjustment may be effected without changing the position of the reamer bar 2, simply by loosening the bolt 15 and sliding the arm 13 into the desired angular position with respect to the reamer bar supporting bracket 2. The bolt is then tightened when the bearing 16 is in alignment with the camshaft bearing 24. The simplicity of the device and the ease with which it may be

manipulated will be appreciated by those familiar with the reaming of crankshaft and camshaft bearings. Obviously, my device may be employed wherever bearings are to be reamed, but, for purposes of illustration, the operation has been described in connection with the reaming of crankshaft and camshaft bearings of internal combustion engines.

The operation of the device is as follows: 75

The bearings to be reamed are exposed by removing the usual bushings and temporary bushings of proper size are inserted in the bearings for aiding in aligning the reamer bar. The brackets are then secured to the crank case, the single attaching means for the several arms are loosened and the reamer bar inserted in the universal self-aligning bearings 19 in the arms 13. The bar is then properly aligned with respect to the bushings and all of the single fastening means for the several adjusting arms tightened. This results in perfect alignment of the reamer bar in the floating universal bearings in the several bearing arms, which alignment remains fixed and uniform until the reaming operation is completed. The temporary bushings are then removed and the reamer bar then rotated to ream the bearings in the crank case so that when reamed properly new bushings may be installed with the assurance that the crank shaft will thereafter be properly aligned in such bearings and bushings.

It is to be observed that the mechanism 100 of the present invention enables quick and positive adjustment of the several bearing arms so that all danger of boring bar cramping or springing is eliminated. Furthermore, every one of the universal bearing arms 105 is secured to its bracket by a single fastening means, thereby allowing quick, easy, and certain adjustment of such arms.

The apparatus of the present invention requires little skill to properly set up for reaming, is extremely accurate and mechanically correct. The provision of the floating universal self-aligning bearings in the several arms assures at all times that the reamer or boring bar is properly aligned with respect to the bearing surfaces to be reamed; furthermore, the bar is supported so as to secure uniform, even, and accurate results.

I am aware that many changes may be made in the construction of my device without departing from the principles of this invention and I therefore, do not purpose to limit the patent granted hereon, otherwise than necessitated by the prior art.

I claim as my invention:

A reamer bar support comprising a bracket, an arm connected to said bracket at the central portion thereof and arranged for longitudinal and angular adjustment about its connection, a bolt passing through said

bracket and said arm for adjustably positioning said arm on said bracket, a universal bearing in one end of said arm, said bearing including a block having a spherical surface, said arm being split in a plane parallel to the sides of the arm, the split portions having concave recesses which together receive and retain said block in position when said parts are secured together to permit universal movement of said block within said recesses, and said block having an aperture for a reamer bar.

In testimony whereof I have hereunto subscribed my name at Chicago, Cook County, Illinois.

RALPH WISHON.
